UNITED STATES PATENT OFFICE.

OSCAR H. JUNG, OF MILWAUKEE, WISCONSIN.

FUSE PLUG.

Application filed May 8, 1922. Serial No. 559,271.

To all whom it may concern:

Be it known that I, OSCAR H. JUNG, a citizen of the United States, and resident of Milwaukee, in the county of Milwaukee and 5 State of Wisconsin, have invented certain new and useful Improvements in Fuse Plugs; and I do hereby declare that the following is a full, clear, and exact description thereof.

10 This invention relates to fuse plugs and is particularly directed to a fuse plug having a body portion of fibre and a surrounding metal ferrule and suitable end portions.

The invention refers to socket fuse plugs. 15 Heretofore it has been common practice to provide fuses of this general type with some transparent surface, whereby the fuse can be usually inspected to determine whether or not it has been blown. In such instances, 20 the visual signal has been found to be impractical, for the reason that the transparent surface provided for inspection frequently becomes blurred and it is, therefore, difficult to determine whether or not the fuse is 25 burnt or blown. The invention, therefore, provides a simple, economical and effective means, whereby the fuse can be physically tested as to its condition.

In the manufacture of porcelain plugs, the 30 porcelains are apt to be cracked in handling, particularly when caps are clinched thereon. This creates a danger of short circuit. By making his shell of fibre, applicant avoids this danger.

35 Most plugs depend upon venting. About the outer edge of caps gases are expected to escape around the clinched edge. This is generally unreliable, as uniform operation depends upon uniform clinching, a practical impossibility due to variations of porcelain. In applicant's device, the provision of five 40 uniform vent holes in the cap makes a reliable and uniform venting system. By the use of powder and the restricted venting system, applicant avoids bad flashes, violence, and a smoked exterior.

45 In mica capped plugs there is a possibility of installing mica discs too thin to withstand severe blow outs. The steel caps of uniform thickness in applicant's invention 50 eliminate this danger.

55 In many porcelain plug fuses the variation of porcelain causes caps to fit loosely, permitting vicious venting. Also, caps have a tendency to shift to one side, preventing

uniform clinching. In applicant's novel structure, this defect is prevented.

Most porcelain plug fuses are provided with chambers or recesses to receive the end of the fusible link, which is to be soldered 60 to the screw shell. These chambers or recesses are sealed with various compounds. This is an unreliable operation for it is indeed difficult to make a practically dependable seal. Defective sealing will emit 65 dangerous flashes, generally destroying both plug and cut-out disc, it becoming a dangerous fire hazard, and an object of the invention is the obviating of this unreliable operation.

70 In some porcelain plug fuses an effort is made to pour solder between the screw shell and the porcelain body in order to make contact between the link and screw shell. In many instances this has proven unreliable, resulting in the destruction of both 75 fuse and cut-out. In the novel construction, the links are soldered in plain view. Defects, if any, are readily discovered by the inspector and remedied before the product 80 leaves the factory. A very important feature of the fusible link is the provision of a restricted portion which localizes the blow-out point, thus making for superior 85 performances, as compared with wire or flat strips without restricted portions.

With the above and other objects in view, which will appear as the description proceeds, my invention resides in the novel construction, combination and arrangement of 90 parts, substantially as hereinafter described and more particularly defined by the appended claim, it being understood that such changes in the precise embodiment of the 95 herein disclosed invention may be made as come within the scope of the claim.

In the accompanying drawing, I have 100 illustrated one complete example of the physical embodiment of the present invention constructed according to the best mode I have so far devised for the practical application of the principles thereof, and in which:

Figure 1 is a sectional elevation of the 105 fuse plug embodying the features of the invention, the section being indicated by line 1—1 of Figure 2.

Figure 2 is a cross section on the line 2—2 110 of Figure 1.

Figure 3 is a rear end view of the plug. Fibre shell 10 has secured to one end a metallic ferrule 11 provided with screw threads 12 adapted to be received in the standard socket. Fitted to the rear end is a centrally apertured fibre disc 13 which is secured to shell 10 by inturned flange 14 of ferrule 11. Any suitable non-conducting material can be used in the disc. Ferrule 11 may be secured to shell 10 by cement.

The front end of the shell is closed by metallic cap 15 formed with an outwardly directed flange 16. The flange is thereafter extended so as to form a bead 17 spun over the outer surface and firmly securing the cap.

Fitted through the aperture in disc 13 is a terminal 18. Bifurcations 19, 19' clinch the terminal against disc 13 and the fusible link or runner 20 is soldered to bifurcation 19. Link 20 has a portion 21 intermediate its ends of reduced cross sectional area and one of its ends extends through shell 10, is bent forwardly, and clamped between ferrule 11 and the shell, solder 21' securing it in position. It is apparent that the solder 21' may be applied in a most convenient manner and failure of the solder to secure link 20 to ferrule 11 is practically impossible. Also, the construction of parts is such as to make the mode of soldering link 20 to bifurcation 19 most convenient.

The shell is adapted to receive a suitable powder, not shown. Cap 15 is provided with apertures 22 over which a paper label 23 is positioned adapted to be suitably marked to indicate proper amperage and voltage of the fuse.

The location of the reduced portion 21 of link 20 is most advantageous, as the fusing action will occur along this reduced extent and it is impossible that the action should occur at the end of the link at which point burning might occur. The fitting of parts adjacent the solder 21' is such as to eliminate bad flashes. The provision of vent holes 22 permitting the egress of heated

gases eliminates any tendency towards violence, smoky exterior, and bad flashes. A uniform and reliable venting system results. 50

A coating of varnish is applied to the cartridge and assists in perfecting the protection of the seal from moisture.

Attention is directed to the fact that in practice the label, or membrane, 23, is quite thin and is glued or otherwise attached to the cap 15, whereby the apertures therein are sealed. Hence, when a blow-out occurs, the gases will readily puncture the sensitive membrane, whereby it serves as a visible 60 indicator that the fuse is dead. It should, also, be understood that the thin metallic link 20, at its base, is of greater cross sectional area than the remainder thereof, which remainder, or weakened strand, extends approximately centrally of the shell and is thereafter folded in a loop and connected to the ferrule 11. Owing to the position of this fusible strand, when fusion takes place, the explosion will radiate from 70 approximately the center of the shell 10, whereby the pressure, due to the gases, is exerted uniformly in a radial direction.

I claim:—

In a socket fuse plug having a fibre shell, 75 and an end closure carrying a contact member; the combination of a metallic disc closure for the opposite end of the shell, the same being formed with an outwardly directed flange for nested engagement with the inner walls of the fibre shell end, said flange being thereafter folded over the end edge of the shell, back upon the body thereof and crimped down upon the outer surface of the shell, whereby the same is compressed 85 between the inner and outer flange walls to effectually seal and prevent blow out of the cap under gas pressure.

In testimony that I claim the foregoing I have hereunto set my hand at Milwaukee, 90 in the county of Milwaukee and State of Wisconsin.

OSCAR H. JUNG.
